UNITED STATES PATENT OFFICE.

PHILIP A. BOWEN, OF LYNN, MASSACHUSETTS, ASSIGNOR TO LILLIAN A. LITTLE, OF LYNN, MASSACHUSETTS.

GRADE-CROSSING PROTECTING SYSTEM.

Application filed July 14, 1925. Serial No. 43,537.

The invention relates to grade crossing protecting systems for railroads. The object of the invention is to provide a system of protective devices which shall be automatically operated by the moving train to warn street traffic of the approaching train and also to provide a barrier to prevent street vehicles and pedestrians from entering the crossing if they disregard the warning signals.

One feature of the invention relates to an audible signal; another feature relates to a visible signal and another feature relates to the provision of a barrier which is automatically moved into operative position as the train approaches the crossing and which is automatically returned to its normal inoperative position when the train passes the crossing, the audible signal and the visible signal being also automatically controlled by the movement of the train.

The foregoing and other objects of the invention, together with means whereby the same may be carried into effect, will best be understood from the following description of the several embodiments thereof as illustrated in the accompanying drawings. It will be understood, however, that the particular constructions described and shown are for illustrative purposes merely and that the invention as defined by the claims hereunto appended may be otherwise practised without departing from the spirit and scope of the invention.

The drawings illustrate the invention as applied to a two-track railroad in which the system embodies all three of the above mentioned forms of the invention and in which a double set of guards and signals are employed, one for each track and both sets are operated by a train moving on either track.

In the drawings:

Fig. 1 is a plan view of a grade crossing system equipped with apparatus embodying the invention.

Fig. 2 is a section taken on the line 2—2, Fig. 1.

Fig. 3 is a similar view to Fig. 2 showing the parts in the position they occupy when a train is passing over the crossing and operating the system.

Fig. 4 is an end view of the parts shown in Fig. 3.

Figs. 5 and 6 are detail sectional views of the three-way valve, in Fig. 5 showing the

valve in the normal position and in Fig. 6 showing the valve in the position during the operation of the apparatus.

Fig. 7 is a vertical sectional view showing a modified form of apparatus embodying the invention.

Fig. 8 is a plan view showing another modified form in normal position.

Fig. 9 is a vertical section taken on the line 9—9, Fig. 8.

Fig. 10 is a view similar to Fig. 9 showing the parts in operative position.

Fig. 11 is a section taken on line 11—11 of Fig. 10.

Referring to the drawings:

A and B represent two parallel railroad tracks and C the roadway for automobiles and other street traffic as well as pedestrians. Preferably the roadway has converging guides D to direct the traffic to the crossway but this feature forms no part of the present invention.

There is shown at E a bell in which the circuit is normally open, at F an electric lamp in which the circuit is normally open and at G a barrier which is normally down out of operative position as shown in Fig. 2 but which as the train approaches the crossing is moved up into operative position in the middle of the roadway adjacent the crossing as shown in Fig. 3.

Compressed air is preferably employed as the power for actuating the several guard and warning devices through suitable intermediate mechanisms controlled by the moving train, although other forces or sources of power with suitable mechanism adapted to be actuated thereby may be employed in lieu of compressed air and yet come within the scope of my invention as set forth hereinafter in the claims.

At 11 is shown a compressed air tank which is kept supplied with compressed air by a pump 12 through connections as will be hereinafter described. The tank 11 and the pump 12 may be located at any convenient place. Preferably and as shown in the drawings the tank 11 is located in a pit under the tracks A, B and the pump is located at one side of the tracks. The air is forced into the tank through an outlet pipe 13 leading from the pump, a three-way valve 14 and an inlet pipe 15 leading from the three-way valve to the tank.

Normally the valve plug 21 is positioned

so that there is open communication between the pump and the tank through the ports 17 and 18, in the valve casing and port 3 in the valve plug, see Fig. 5. The valve casing has 5 a port 19 which communicates with a pipe 20 to conduct the compressed air to operate the signal and guard mechanism, but said port 19 is normally closed by the plug 21. An arm 2 projects from the plug 21 of the 10 valve and is adapted to be engaged by a projecting member on one side of a car or locomotive of the train to put the system into operation. It is not deemed necessary to show the train with the projecting member 15 as this may be well understood without illustration. A connecting rod or wire 23 is connected at one end with said arm 2 and at its other end with one arm of a lever 24 pivoted at 25 alongside of the track in position 20 so that the other arm 24^a of said lever 24 is adapted to be engaged by the said projecting member on the train as the train passes beyond the crossing to operate the system whereby the devices may be returned 25 to their normal position.

The operating arm 2 of the valve 14 is located at a point some distance before the crossing in order that the protecting apparatus may be operated in ample time before 30 the train reaches the crossing.

The connecting rod or wire 23 is long enough so that the lever 24 may be located at a point some distance from the crossing in order that the protecting apparatus may return to its normal position after the train 35 has passed beyond the crossing.

When the train in approaching the crossing on the right-hand track A in the direction of the arrow, the actuating member on 40 the car or locomotive will engage the arm 2 of the valve 14, thereby turning the plug 21 into the position shown in Fig. 6 so as to close the communication between the pump 12 and the tank 11 and open the communication 45 between the tank 11 and the pipe 20. At the same time the arm 2 will, by means of its connection with the lever 24, move the arm 24^a into the path of movement of the actuating member. When the train has 50 passed over the crossing the actuating member will engage the arm 24^a of the lever 24, and through the connection between said lever and arm 2, will turn the valve back into the position shown in Fig. 5, thereby cutting 55 off the supply of compressed air to the protecting apparatus and permitting the parts to return to their normal position.

A pit 26 is provided in the roadway at one 60 side of the track to contain the guard and signal mechanism. The barrier member G consists of a platform 27 which normally lies on a level flush with the surface of the roadway and forms a cover for the pit. The platform is hinged at 28 on the side nearest the track. The opposite side edge of the

platform normally rests on a support 29 to maintain the platform in level position so that vehicles may safely drive over it. Preferably it is provided with a downwardly extending flange 30 so that when the platform is tipped up as shown in Fig. 3 the flange 30 will close the entrance to the pit and also will serve as a barrier to vehicles. 70

Mounted in the pit is a cylinder 31 in which is mounted a vertically slideable piston 32. A pipe 33 opens at one end into the said cylinder 31 below the piston 32 and at its other end communicates with the compressed air pipe 20 so that when the plug 21 of the three-way valve 14 is turned to open communication 75 between the compressed air tank 11 and pipe 20, compressed air will be admitted into the lower part of the cylinder 31 to raise the piston 32 as shown in Fig. 3.

Mounted on the upper end of the piston 32 is an arm 34 which when the piston moves upward engages the under side of the platform 27 and turns said platform up on its hinge as shown in Fig. 3. 80

Mounted on the top of the piston is a lamp 90 F which preferably has a stem 5 to hold the lamp F in a somewhat elevated position when the piston rises. The platform 27 is formed with an opening 6 through which the lamp will be projected upward when the piston rises so that the lamp will then be sufficiently elevated to be visible to occupants of approaching vehicles or pedestrians. 95

Normally the circuit through the electric lamp will be open. Means are provided 100 whereby the circuit through the lamp will be closed when the piston moves up to raise the platform. The mechanism shown is as follows: A contact member 7 is mounted at the side of the pit, said contact member being stationary and forming a terminal for the wire 8 leading from the battery 9. Carried on the side of the piston 32 is a contact member 10 which when the piston rises will make contact with the member 7 and thereby 105 close the circuit through the lamp. 110

The electric bell E is also mounted in the pit or in some other suitable place wired up in connection with the battery 9 and with the wire 8 so that when the electric circuit 115 is closed by the rising of the piston 32 to bring the contact member 10 in contact with the terminal member 7, the circuit will be closed and thereby the bell or gong will be sounded. It is not deemed necessary to describe in detail the mechanism or the electrical connections with the gong as this may be of any well known form of construction. 120

It will thus be obvious that when a train 125 is approaching the crossing in the direction indicated by the arrow on the track A in Fig. 1, the arm 2 will be engaged by the projecting member on the train so as to turn the plug of the three-way valve 14 to open communication between the compressed air 130

tank and the pipe 20 and thereby admit compressed air to the lower part of the cylinder 31, raise the piston 32 which will lift the platform 27 from the position shown in Fig. 5 2 into the position shown in Fig. 3, close the circuit to turn on the light in the lamp F and operate the gong E.

At the same time the lever 24 will be set so that the arm 24^a of said lever will be in 10 the path of movement of the projecting member on the train and when moved by said projecting member will so position the parts as to permit their return to normal position after the train has passed over the 15 crossing.

A corresponding equipment of platform or barrier, electric light and gong are located on the opposite side of the track and they will be simultaneously operated with 20 the apparatus on the side of the track A. In order to accomplish this, it is not necessary to have a separate air pump, but air may be admitted to the cylinder 31 in the equipment on the side of the track B by 25 suitable connections with the tank 11. A pipe 40 communicates at one end with the pipe 20 through a suitable union and at its other end communicates with the lower part of the cylinder 31 on the side of the track 30 B so that compressed air will be admitted to the said cylinder at the same time it is admitted to the cylinder 31 on the side of the track A, and the platform, light and gong will be operated simultaneously with 35 the set of apparatus previously described for the track A.

The trains running on track B will move in the opposite direction from those on the track A as shown in the drawings. Means 40 are provided whereby when the train is moving on track B the apparatus on both sides will also be simultaneously operated. An outlet pipe 41 leads out of the compressed air tank 11 and communicates with 45 a valve 42 similar to the valve 14 and having an arm 43 with which one end of a connecting rod 44 is connected, the other end of said connecting rod or wire being connected with one arm of a lever 45 pivoted at 46 and provided with an arm 45^a similar to the arm 24^a of the lever 24. The arm 43 will be actuated by the moving train in the same manner as the arm 2 connecting with the other set of apparatus as already described. This will admit compressed air 55 from the tank 11 through the pipe 41, valve 42, and pipe 47 to the pipe 40 previously referred to, and thence through the pipes 33 and 48 with which it connects to the cylinders 31 to operate the apparatus on each 60 side of the crossing.

At the same time the lever 45 will be set so that the arm 45^a of said lever will lie in the path of movement of the projecting member of the train, so that when the arm

is moved by the said projecting member, the parts may be permitted to return to their normal position after the train has passed over the crossing.

In the modification shown in Fig. 7 the 70 apparatus is so constructed and arranged that the electric lamp will be raised into view and rendered operative before the barrier is raised. In this form the lamp will be mounted on the piston 32 and operated 75 as already described. The battery and electric connections are omitted from the drawings in Fig. 7 as being unnecessary to illustrate the modification.

The hinged platform 27 instead of being 80 operated by the piston 32 which carries the lamp is operated by a separate piston 50 slideable in the cylinder 51 and having a stem 52 whose upper end is pivotally connected with the platform 27. The compressed air 85 for raising the piston 50 is introduced into the cylinder 51 through a pipe 53, one end of which communicates with an outlet port 54 in cylinder 31 and the other end of which communicates with the interior of the cylinder 51. The port 54 is so located that it is normally closed by the piston 32 and is not uncovered until the piston 32 rises far enough for its lower end to pass above the port 54. The lamp F will in the meantime 90 have passed up through the opening 36 in the platform 27 and display the light. The piston 50 will then rise and tip the platform 27 on its hinge 28, thereby raising the unhinged side of the platform into operative 95 position as already described and shown in Fig. 3.

In the modification shown in Figs. 8-11 inclusive instead of employing a hinged platform as the barrier there are employed a 105 plurality of lamps arranged in a row transversely of the roadway approach to the crossing and so mounted on standards that the lamps and their mounts will serve the double purpose of barrier and signal light. 110 Each lamp F is mounted on a long stem or standard 55. Connected with the lower end of the stem 55 is an arm 56 which projects at an angle to the stem and is formed with an elongated slot 57 which is engaged by one end of a lever 58 pivoted at 59 intermediate its ends. The standard and the arm together thus somewhat resemble a bell crank lever with one short arm and one long arm, said lever being fulcrumed at 90. The engaging end 60 of the lever 58 is shown as an extension of reduced cylindrical form for smoothness of operation and to lessen the friction in its engagement with the slot. 115

Normally the series of standards 55 with 120 the lamps mounted thereon will lie prone in a slot S on the roadway as shown in Fig. 9. Means are provided whereby they will all be turned up into vertical position, as shown in Fig. 10 when a train approaches the 125

crossing so that they will then have the appearance of a row of pickets extending cross-wise of the roadway.

The lamp standards will be operated by a projecting member carried by the train as previously described acting on the bell crank lever 61, and by intermediate mechanism, connecting said lever 61 with the levers 58. There are two levers 61 located on opposite sides of the crossing. The levers 61 are fulcrumed at 62. The free arm of one lever 61 normally projects into the path of the actuating member carried by the train. A connecting rod or wire 63 connects the arms 64 of the two levers 61 so that the said two levers will be operated simultaneously.

Each of the levers 58 has a pin and slot or other flexible connection with a longitudinally slidable rod 65, and said rod 65 has operative connection with the rod 63. The connection shown comprises a bell crank lever 66 having one arm connected to the rod 63, a bell crank lever 67 having one arm connected with the rod 65 and a rod or wire 68 connecting the two levers 66 and 67. The slot S which contains the lamps and standards is preferably provided with hinged covers 70 as indicated in Figs. 9 and 11. These covers are adapted to be turned up on their hinges by a projection 72 when the lamps are tipped up into operative position. Each cover is provided with an arm 71 which, when said cover is in raised position as shown in Fig. 11, is adapted to be engaged by a projection 72 on the lamp standard and thereby close said cover when the lamps are being returned to their normal position.

It is obvious that when a train is traveling in the direction of the arrow on track A and the free arm of the bell crank lever 61 at the left of Fig. 8 is engaged by the projecting member on the train, the rod 63 will be moved longitudinally toward the left and the rod 65 will be moved toward the right, thereby turning the levers 58 on their pivots from the position shown in Fig. 8 toward the right and turning the lamp standards up from their prone position shown in Figs. 8 and 9 into vertical position, as shown in Fig. 10. When the lamp standards are turned up into operative position, the electric circuit will be closed through the lamps and through the gong to light the lamps and sound the gong.

At the same time the free arm of the lever 61 at the right of Fig. 8 will be set in the path of movement of the projecting member on the train, so that when it is engaged by said projecting member after the train has passed over the crossing, the parts will be returned to their normal position.

A corresponding equipment of operating mechanism, lamps and gong are located on the opposite side of the tracks and will be 65 operated by a train coming in the direction of the arrow shown on track B.

While I have shown the lamps as located at the sides of the tracks in the drawings, I do not wish to limit myself to this construction as they might equally well be placed between the tracks A and B, in which case only one set of lamps would be necessary.

While I have described the different forms 75 of my apparatus as operating when a train is going in a forward direction, it will be obvious that the mechanism might be designed so as to operate the apparatus when a train is backed over the crossing.

What I claim is:

1. In a grade crossing protecting system, the combination of a barrier normally supported at or below the level of a roadway, a lamp support having a lamp and normally located beneath the barrier, and mechanism for elevating said barrier and for elevating 85 the lamp to a visible portion above the barrier.

2. In a grade crossing protecting system, 90 the combination of a swinging barrier normally located at or below the level of the roadway, a lamp support having a lamp and normally located below said barrier, and mechanism for shifting said lamp support 95 relatively to the barrier and for raising the barrier, whereby the lamp will be visible and the barrier in operative position.

3. In a grade crossing protecting system, 100 the combination of a swinging barrier normally located at or below the level of the roadway, a lamp support having a lamp and normally located below said barrier, and means for shifting said lamp support relatively to the barrier to raise the latter into 105 operative position and to bring the lamp into visible position.

4. In a grade crossing protecting system, 110 the combination of a swinging barrier normally located at or below the level of the roadway, a lamp support having a lamp and normally located below said barrier, and means for shifting said lamp support into engagement with the barrier to raise the latter and to elevate the lamp above the barrier. 115

5. In a grade crossing protecting system, 120 the combination of a barrier having an aperture, a signal lamp below said barrier, means for elevating said barrier and for shifting the lamp through said aperture to a visible position above the barrier.

In testimony whereof I affix my signature.

PHILIP A. BOWEN.
